UNITED STATES PATENT OFFICE.

CHARLES S. VAN NUIS AND JOHN W. ACHARD, OF PHILADELPHIA, PENNSYLVANIA.

MECHANISM FOR OPERATING DISTANT CIRCUIT-BREAKERS.

1,051,929.

Specification of Letters Patent.

Patented Feb. 4, 1913.

Application filed February 18, 1907. Serial No. 357,820.

To all whom it may concern:

Be it known that we, CHARLES S. VAN NUIS and JOHN W. ACHARD, both citizens of the United States, and residents of Philadelphia, in the county of Philadelphia and State of Pennsylvania, have jointly invented certain new and useful Mechanism for Operating Distant Circuit-Breakers, of which the following is a specification.

10 In electrical installations it is often necessary or desirable to locate a circuit breaker at a point distant from a power house or other station where the attendants are assembled. This is especially true in connection with storage batteries which are often located out upon a line and while not requiring a constant attendant, yet involve the use of a circuit breaker.

20 The principal object of the present invention is to provide for satisfactorily and reliably resetting distant circuit breaking mechanism from a central station, or other place where attendants are required, thus obviating the necessity for the constant presence of an attendant at the distant circuit breaking mechanism and thereby in many cases effecting material economies.

25 The nature and characteristic features of the invention will be more fully understood 30 from the following description taken in connection with the accompanying drawings forming part hereof, and in which—

35 Figures 1, 2, and 3, are respectively a front, rear and side elevation partly in section of the mechanism which is located at the distant point. Fig. 4, is a view partly in section illustrating a detail, of the mechanism shown in the above mentioned figures. Fig. 5, is a diagrammatic view of mechanism embodying features of the invention. Fig. 6, is a transverse sectional view taken on about the center line of the right hand part of the device shown in Fig. 1, looking toward the left. Fig. 7, is a similar view 45 of the device shown at the left in Fig. 1. Fig. 8, is a central sectional view of a solenoid, shown at the right in Fig. 3. Fig. 9, is a view like Fig. 1, and illustrating a modification, and Fig. 10 is a view illustrating the details of construction of the mutilated gears shown in Fig. 3.

40 Referring to Fig. 5, there is arranged at a suitable station where attendants are present, for example, at the central station or power house, mechanism illustrated at the bottom of the figure and there is arranged

5 at a point distant from the central station or power house, for example, at a sub-station where an attendant need not be present, the mechanism illustrated at the top 60 of the figure. At the power house or central station there is a generator indicated at 1, and also signal mechanism shown in the drawings to comprise a bell 2, a resistance 3, and lamps 4. However, all these 65 signaling apparatus need not be employed and a variety of it is shown merely to indicate a signaling apparatus of some kind. At the sub or distant station there is a storage battery 5, circuit breakers 6 and 7, 70 of which one 7, is shown to be of the automatic variety and at least one of them or if desired, both of them may be of that variety. These circuit breakers 6 and 7, are provided with auxiliary switches 8 and 9. 75 There is also a motor 10, and a switch 11, for making and breaking its circuit to stop and start it. This switch 11, is closed by an electro-magnet 12 Fig. 8 and is released by an automatic locking device 13 operated 80 through the intervention of parts driven by the motor 10. The motor 10, also operates through the intervention of parts that will be described to perform a cycle which consists in first tripping both circuit breakers 85 6 and 7 (of course if one of them has tripped only, the other of them is tripped through the operation of the motor) then closing one of them which must be automatic and finally closing the other of them. 90

For the sake of explanation a description will first be given of the mechanism last referred to and thereafter a description will be given of the various circuits.

95 The circuit breakers 6 and 7, are shown in Fig. 1, as arranged side by side upon a suitable panel 14. The circuit breakers chosen for illustration are of the general electric type and need not be fully described, as they are well understood. The circuit breaker 7, 100 since it is of the automatic type is provided with a series coil 15, the arm 16, the operating handle 18, the trip lever 19 for releasing the arm 16 and the lever 20 for operating the trip lever 19 and thereby releasing the 105 arm 16 without relying upon the action of the series coil 15 upon an armature which also releases the trip lever. In the case of the circuit breaker 6, which is not required to be automatic the coil 15 and lever 20 are not 110 present, nor is the arm 16 provided with an extension 21.

Otherwise than has been stated the circuit breakers are alike and of the variety mentioned, but the invention is not limited to any special form of circuit breaker as the elements referred to are to be found in a variety of them.

22, is a shaft suitably journaled and driven by the motor 10, shown as arranged upon the back of the panel 14, Fig. 2. The motor 10, drives the shaft 22 through the intervention of suitable gearing.

As shown in the drawings a worm 23 on the motor shaft projecting through the panel is shown to engage a worm-wheel 24 on the shaft 22. There are shafts 25 and 26, which have rotary motion imparted to them from the shaft 22. As shown this is accomplished by means of gears 27 and 28, and 29 and 30. The rotation of the shafts 25 and 26 operates to trip or release and open the circuit breakers. As shown this is accomplished by means of a pair of links 31 and 32, pivoted together. The links 31 are shown, Figs. 6 and 7, as arranged loose upon the shaft 22 and the links 32 are provided with straps encircling eccentrics on the shafts 25 and 26, so that in each case as the eccentric turns the point of articulation of the pair of links is projected toward the panel and withdrawn from the panel. In the case of the circuit breaker 7, the point of articulation of the links 31 and 32 is arranged to collide with the lever 20, Fig. 6, which as has been said operates the trip lever 19. In the case of the circuit breaker 6, Fig. 7, the trip lever 19, is turned downward and a link 33, having one end pivoted at 34, and having its other end free and disposed in front of the trip lever 19 is arranged in such position that the point of articulation of the links 31 and 32 collides with substantially the center part of the face of the link 33, thus shifting the link 33 backward which motion of the link in turn shifts the trip lever 19 and releases the circuit breaker arm. The rotation of the shafts 25 and 26 also operate to close the circuit breakers. This is accomplished as shown in the drawings by providing the wheels or gears 27 and 29 with lugs or studs 35 and 36 arranged in such position that during a portion of a revolution of the wheels they collide with lugs 37 and 38, projecting laterally from the arms 71 of the circuit breakers. The axis of the wheels and the pivot of the arm 71 are not concentric, hence the lugs 37 and 38 slide past and clear of the studs 35 and 36, upon the completion of that portion of a revolution. Inasmuch as a circuit breaker having its arm provided with an extension 21 which carries a carbon block should not be closed with too much force whereas a circuit breaker from which these provisions are absent can be closed with as much force and rapidity as desirable, we

have shown means whereby the circuit breaker 7 may be closed comparatively gently and slowly and the circuit breaker 6 closed rapidly and with considerable force. These means comprise the provision of gear wheels 27 and 28 of proper relative diameter having teeth all around each of their circumferences and they comprise the provision of wheels 29 and 30, of proper relative diameter and of which the wheel 30 has teeth only around a portion of its circumference so that the wheel 30 may turn for a part of a revolution without turning the wheel 29 at all and during the rest of its revolution its teeth will engage the teeth of the wheel 29, and turn that wheel very rapidly in comparison with the speed of turning of the wheel 27. From this it follows that the circuit breaker 7 will be closed slowly and gently in accord with the rotation of the shaft 22, whereas the circuit breaker 6 will be closed rapidly and only during the intermittent portions of the revolutions of the shaft 22. By properly timing the described pause in the movement of the wheel 29, it may be made to occur when the stud 35 is still in engagement with the lug 37 after having closed the circuit breaker, thus the circuit breaker may be positively held in closed position, until the wheel 29 starts again,—when this arrangement is used the switch 8 and its connections to the circuit 58 are unnecessary. During each pause one of the concavities *a*, on the rim of the wheel 29 rests on the blank part of the periphery of the wheel 30, and thus the wheel 29 is held against accidental movement.

The auxiliary switches 8 and 9 comprise a circuit closer shown to consist of an insulating sleeve 48, Fig. 4, carrying contacts and a spring actuated plunger 49 provided with a conducting piece for bridging these contacts and closing circuit between them. The plunger 49 is arranged so as to be released by a portion *A*, of the movable arm of the circuit breaker when the circuit breaker opens and is thus shifted in position for closing the circuit at the bridge piece, and when the circuit breaker is closed it shifts the plunger so as to open the circuit.

Referring to Fig. 2, the casing 12, contains an electro-magnet, the core of which tends to drop by gravity and is lifted when the coil is energized. The coil carries the motor switch 11, so that when the electro-magnet is energized the switch 11 is closed and when the magnet is deenergized, the switch would open except that it is detained by a bolt 39. The bolt 39 projects from a cylinder arranged in a barrel 40, along with a spring 41, which tends to cause the bolt to engage a notch 42 in the spindle of the switch 11 so as to lock the switch in closed position. There is a bar 43, reciprocatingly arranged in bearings and provided with in-

sulation and means shown to consist of a nut and thread for adjusting its length. 43 and 44 are links pivoted together at 45 and the link 43 is pivoted to the frame work 5 or panel 14 and the link 44 is pivoted to the bar 13^a. 46, is a spring connected with the bar 13^a, at one end and with the panel or frame work at the other end. There is a rod 47, which extends through a slot in the panel and is centrally pivoted at 47^b and has one of its ends pivoted to the point 45 of articulation of the links 43 and 44, and at its other end is provided with a strap which engages an eccentric 50, on the shaft 26, so that as the shaft 26 rotates the rod 47 oscillates and in its oscillation acting upon the links 43 and 44, reciprocates the rod 13^a. This rod 47, is connected at the point 45 by the provision of a fork 47^a on its end and it is centrally pivoted by means of a slot-and-pin connection 47^b, Fig. 3. The slot connections are availed of so as to take up the throw of the eccentric 50. The parts last described are so arranged and their movements are so timed that when the magnet 12 is energized and the switch 11 closed, the motor 10 rotates the shaft 26 through the instrumentalities described and the rotation of this shaft acting upon the rod 47, through the intervention of the cam 50, causes the rod 47, to so position the links 43 and 44 that the spring 41 drives the catch 39 into engagement with the notch 42, thus the switch 11, is locked in closed position and will remain closed until the motor has driven its connected parts through one of the described two portions of the cycle in which both circuit breakers are tripped, thereupon the cam 50 will have reached such position that its action upon the rod 47 and links 43 and 44 will result in shifting the rod 13^a, in such position that the catch 39 releases the sleeve of the switch 11, which will thereupon open. The next time that the electro-magnet 12 is energized the described operations will be repeated and the switch will be locked in closed position in the manner described and so held until the completion of the next portion of the cycle of operations 120 which results in the closing of both circuit breakers and there being left free to again be opened.

Referring to Fig. 5, 51 and 52 are the leads of a working circuit across which there is a load. The battery 5, is arranged by means of conductors 53 and 51 for connection across this working circuit. Connected around the battery is a circuit 55-56 in which is included the motor 10, and the motor switch 11. The circuit breakers 6 and 7, are interposed between the conductors 51 and 53, and 52 and 54 respectively and the series coil 15, of the circuit breaker 7, is shown as interposed in the conductor 52. There is also a single conductor 59 which

extends from the central station to the sub-station. At the central station end this conductor 59 may be connected by means of a switch 60 either to a conductor 61 that leads to the line 52, or to a conductor 62 that leads to the line 51 and contains the signaling apparatus which has been described. At the other end this conductor 59 is provided with a branch 63 containing a resistance 64 and which is connected to the loop 58. The conductor 59 is also provided at this end with a branch 65 that contains a resistance 66, includes the coil of the magnet 12 and is connected to the lead 51.

The mode of operation of the described apparatus may be explained as follows: Assuming that the circuit breakers 6 and 7, are closed and that the switch 60 is in the position shown on Fig. 5, there exists a condition of affairs in which the battery and the generator, are both connected to the line 51-52. The auxiliary switches 8 and 9, under such circumstances are, of course, open. If, for any reason, such as an overload, the circuit breaker 7 should automatically open 90 which, of course, is its intended function, the auxiliary switch 9, will be closed. Under such circumstances a circuit will be established in the signaling system by way of conductor 57, conductor 58, through auxiliary switch 9 to conductor 59, through resistance 64, through switch 60, through the signaling apparatus and through the conductor 62 to the line 51. The effect of this current is to operate the signaling mechanism and direct the attention of the attendants at the central station to the fact that a distant circuit breaker has opened. When the circuit last described is established a portion of the current passes by conductor 65 through resistance 66, and electro-magnet 12 to line 51, but this portion of the current has traversed both of the resistances 64 and 66, and is therefore not sufficient to energize the magnet 12 enough to cause it to lift 110 its armature and close the motor switch. In fact, the coil of the magnet 12 is so designed that current passing the resistance 64 and 66, in series is insufficient to energize it enough to cause it to lift its core; however, current passing one of these resistances is sufficient for this purpose. If the circuit breaker 6 instead of the circuit breaker 7, has opened for any cause and it has already been said that it might be an automatic circuit breaker, the signaling circuit would have been established from 57 by way of 58, through the auxiliary switch 8 and thence by way of 63 through the resistance 64 to the line 59 and the signaling mechanism 125 would operate in the manner described. In Fig. 9 the circuit breaker 6^a is an automatic circuit breaker and it is shown as just like the circuit breaker 7 in Fig. 1. It differs from the circuit breaker 6, in that it 130

opens in response to an overload, whereas the circuit breaker 6 does not do so. Since the circuit breaker 6, Fig. 9, comprises parts corresponding exactly with the parts of the circuit breakers 7 and 8, the same reference letters have been applied. When the attendant at the central station receives the signal indicating the opening of a distant circuit breaker, he pushes switch 60, so as to complete the circuit from 61 by way of 59 through 65, resistance 66, electro-magnet 12 and to line 51. The effect of this is to energize the magnet 12 sufficiently to close the motor switch. There may also be a circuit 10 by way of 63 through a portion of the loop 58 through 57 to 52, but this is unimportant. When the motor switch is thus closed the motor 10 receives current by way of the circuit 55, and 56 and starts. The starting 15 of the motor sets in motion the mechanism which locks the switch 11 in closed position and also the mechanism which trips both the circuit breakers. The object in tripping both the circuit breakers is to be sure that 20 they are both open so that an automatic circuit breaker may be thereafter first closed and left in position to automatically open before the other circuit breaker is closed. The purpose of this is that in the event of 25 a permanent short circuit as distinguished from a temporary overload the automatic circuit breaker may be free to immediately open as soon as the second circuit breaker is closed, thus avoiding possible danger from 30 excessive currents. As soon as both of the circuit breakers have been tripped or opened in the manner described the switch 11 is released through the operation of its catch 35 under the influence of the movement of the parts driven by the motor, thereupon 40 the motor stops. The attendant having thus tripped both circuit breakers would probably wait for a short interval of time until the overload might have ceased and he then 45 again closes the switch 60. The result of this is that the circuit for energizing the magnet 12 is again established and the magnet 12 closes the switch 11, thus again starting 50 the motor and locking switch 11 in closed position until the remainder of the cycle is completed and the circuit breakers are closed. First the automatic circuit breaker is closed and released so as to be free to open again, then the other circuit 55 breaker is closed and the motor switch permitted to open. If the difficulty was a temporary overload both circuit breakers will remain closed, but if the difficulty has not been temporary but was due to a short circuit or a prolonged overload, as soon as the circuit breaker 6 is closed the circuit breaker 7 will under the influence of its coil 15 open, thus the circuit breaking mechanism located at a distance from the attendant can be operated by him in the same way that it would

be, if it were at hand, for example, to cut the battery or other source at the sub-station off the line.

What we claim, is—

1. The combination of a station, a distant 70 substation, a pair of circuit breakers at the distant station and of which one is automatic and which are provided with auxiliary signal switches, motor driven mechanism for first tripping both circuit breakers and 75 for subsequently closing the same and clearing the automatic circuit breaker, an electro-magnetic switch for closing the motor circuit, means controlled by said motor driven mechanism for detaining said switch in closed position and subsequently releasing it, signaling mechanism at the central station having circuit connections controlled by the auxiliary switches, and a single wire provided with a switch at the central station, 80 which wire constitutes a part of the signaling circuit and also means for conveying current through the magnet of the motor switch, substantially as described.

2. In combination a pair of circuit breakers, motor driven mechanism for first tripping both circuit breakers and thereafter closing them in succession and leaving them free to again trip, a motor switch electro-magnetically closed, and means controlled 95 by the motor driven mechanism for locking said switch in closed position during a pre-determined cycle of operations of the motor driven mechanism, substantially as described.

3. The combination of a pair of circuit breakers having arms, a driving shaft, lugs or studs for engaging the arms and closing said circuit breakers, and gearing interposed between said shaft and the respective studs 105 or lugs and whereof that gearing which appertains to one of the circuit breakers is of the intermittent type and that gearing which appertains to the other circuit breakers is of the continuous type and of greater speed 110 reduction than the first, whereby one of the circuit breakers is closed gently and the other rapidly with the rotation of the shaft.

4. The combination of a pair of circuit breakers, a driving shaft, a pair of counter-shafts, gear wheels interposed between the driving shaft and counter-shafts, and provided with means for closing the circuit breakers, and cam driven mechanism for tripping said circuit breakers, substantially 115 120 as described.

5. The combination of a pair of circuit breakers, a driven shaft and motor for driving said shaft, a pair of counter-shafts, gearing between the driven shaft and the 125 counter-shafts provided with means for closing the circuit breakers, mechanism responsive to the motion of said shafts for tripping the circuit breakers, an electro-magnetic motor switch, mechanism for locking 130

said switch, and devices interposed between the counter-shaft and the locking mechanism for releasing the latter upon the completion of a predetermined cycle of operations, substantially as described.

6. The combination of a pair of circuit breakers, a driven shaft and motor for driving said shaft, a pair of counter-shafts, gearing between the driven shaft and the 10 counter-shafts provided with means for closing the circuit breakers, mechanism responsive to the motion of said shafts for tripping the circuit breakers, an electro-magnetic motor switch, a spring operated catch 15 for locking said switch, a bar and its complementary pair of toggle levers for operating the catch, and an oscillating rod driven from one of said shafts and connected with the toggle levers, substantially as described.
- 20 7. The combination of a central station, a distant station, a line extending from one station to the other and including a storage battery at the distant station, a pair of circuit breakers at the distant station and of 25 which at least one is automatic and which are provided with auxiliary circuit closers, motor driven mechanism for tripping the circuit breakers and closing them in succession and freeing them, a motor switch elec- 30 tro-magnetically closed, locking mechanism controlled by the motor and adapted to detain the motor switch in closed position dur-

ing the cycle of operations of the motor driven mechanism and to thereupon release the same, a single conductor extending from 35 one station to the other and having at the central station a switch and two branches, of which one is provided with signaling mechanism, a loop circuit from one lead through the auxiliary circuit closers and back to that 40 lead of the line, a branch from the conductor that extends from one station to the other to one side of said loop, and a branch through the electro-magnetic motor switch to the other lead of the line, and resistances 45 in said branches, substantially as described.

8. The combination of a circuit breaker having a pivotal arm provided with a lug, a wheel having its axis out of line with the pivot of the arm, a stud on the wheel in 50 range of the arm whereby rotation of the wheel operates to cause the stud to engage and close the breaker arm, and means for driving the wheel with an intermittent motion in which a pause occurs when the wheel 55 has closed the breaker, substantially as described.

In testimony whereof we have hereunto signed our names.

CHARLES S. VAN NUIS.
JOHN W. ACHARD.
